(57) **CLAIM**

The ornamental design for a steering wheel, as shown and described.

DESCRIPTION

FIG. 1 is front perspective view of a steering wheel showing our new design;

FIG. 2 is a front view thereof;

FIG. 3 is a rear view thereof;

FIG. 4 is a left side view thereof, the right side view being a mirror image thereof;

FIG. 5 is a top view thereof;

FIG. 6 is a bottom view thereof;

FIG. 7 is front perspective view of a second embodiment thereof;

FIG. 8 is a front view thereof;

FIG. 9 is a rear view thereof;

FIG. 10 is a left side view thereof, the right side view being a mirror image thereof;

FIG. 11 is a top view thereof;

FIG. 12 is a bottom view thereof;

FIG. 13 is front perspective view of a third embodiment thereof;

FIG. 14 is a front view thereof;

FIG. 15 is a rear view thereof;

FIG. 16 is a left side view thereof, the right side view being a mirror image thereof;

FIG. 17 is a top view thereof; and,

FIG. 18 is a bottom view thereof.

The dotted broken lines shown in the drawings illustrate portions of the steering wheel that form no part of the claimed design. The dot-dot-dash broken lines illustrate unclaimed boundaries. In FIGS. 13-18, the gray shading represents a surface pattern that contrasts with the surface pattern on the four central spokes, not any particular color.
